UNITED STATES PATENT OFFICE

2,573,362

SHOTGUN PROJECTILE

Ardie A. Rouse, Orange, Tex.

Application June 6, 1947, Serial No. 753,077

1 Claim. (Cl. 102—38)

1

This invention relates to a shotgun projectile, and more particularly to a shotgun projectile that contains a noxious powder.

An object of the invention is to provide a shotgun projectile that can be charged with powder or other comminuted material. In hunting small animals in their hiding places, the use of such a projectile has been found adantageous in marking the quarry. The powder used may be vesicatory or olfactory, or may be just plain face powder or flour.

To this end, the invention contemplates a cartridge comprising a powder-containing projectile in its forward portion, and a propellant charge in its rear portion. After being fired, the cartridge case is of course retained in the gun and subsequently ejected, and the projectile proceeds on its course. On impact, the projectile bursts, and scatters the powder. The projectile is not rifled, but on the contrary is provided with a plurality of fins to prevent it from spinning and to keep it on its course.

The invention will be more clearly understood with the aid of the accompanying drawings, which illustrate a preferred embodiment of the invention.

Figure 1 is a longitudinal section through a cartridge containing the propellant and the projectile.

Figure 2 is an enlarged elevation of the projectile.

Figure 3 is a rear end view of the projectile.

The device comprises a cylindrical cartridge shell 10 which contains a projectile 13 in its forward portion and a propellant charge 14 in its rear portion. The projectile 13 contains the powder or other comminuted material 15 hereinbefore mentioned. The projectile 13 has a boat tail, and is provided with four guiding fins 16.

The rear of the projectile 13 is provided with a central opening for the purpose of filling the projectile 13 with the powder 15, and the aperture is closed with a screw plug 18.

The nose of the projectile 13 is aligned with a central opening 21 in the front portion of the cartridge case 10, to facilitate travel of the projectile 13 through the gun barrel after the propellant charge 14 has been exploded. A cushion wad 22 may be positioned between the propellant charge 14 and the tail of the projectile 13 to prevent the jar of the explosion of the propellant charge 14

from bursting the projectile 13 before the latter has reached its target.

The cartridge 10 may be provided with the usual band 24 and firing cap 26.

The operation of the device is briefly as follows: Detonation of the firing cap 26 will explode the propellant charge 14, and the force of the latter will immediately propel the projectile 13 through the cartridge case 10 and through the gun barrel. On impact, the projectile 13 will burst, and will scatter its contained powder on such objects as are within range.

I claim:

15 In a cartridge for a smooth bore gun, a tubular cartridge case having a closed rear end and a forward end, a wad positioned intermediate the rear and forward ends of said case, a propelling charge in said case between said rear end and said wad, a projectile positioned in the case between said wad and the forward end of the case, means in the forward end of the case defining a relatively small central opening axially aligned with said case, and a projectile confined within said case between said wad and said means, said projectile 20 having a forward end tapered forwardly to a point, said point being positioned in said central opening whereby the projectile is initially guided in its travel from said case into the gun barrel as said propelling charge is exploded.

ARDIE A. ROUSE.
